PRESS

Mieth Maeser, Beverly, Mass., assignor to United Shoe Machinery Corporation, Borough of Flemington, N. J., a corporation of New Jersey

Application March 10, 1939, Serial No. 260,959

15 Claims. (Cl. 164—23)

This invention relates to improvements in presses, particularly to those presses generally referred to as clicking machines, which are employed for driving dies through thin sheet material such as leather, in forming shoe parts.

As ordinarily constructed, such machines have an upper presser member with a pressing surface smaller in area than the cutting block on which the material to be operated upon is held. To enable the machine to act upon a die on any part of the cutting block, the presser member or beam is mounted for swinging movement on a vertically reciprocable post positioned rearwardly of the cutting block. The operator places a die in the desired position on the sheet material and swings the presser member over the die. He then depresses a starting handle thus applying power through a clutch to a drive shaft connected to the presser member, and the latter delivers a downward blow to the die.

It is an object of the present invention to increase the efficiency of machines of this type by causing the presser member to deliver the most effective possible blow to the die, thereby improving the quality of the work done, and decreasing the amount of work spoiled because of poor cuts.

Experiments have shown that the most satisfactory drive for a clicking machine is that which imparts to the die a sharp, quick blow as contrasted with a slower but heavier pressure on the die. In the types of clicking machine now in general use the driving means is an eccentric and eccentric strap, and each revolution of the eccentric imparts a complete cycle of downward and upward movement to the presser member. The eccentric is arranged so that the side farthest from its axis, i. e., the high side, is at the top in starting position. On account of the nature of eccentric movement the point of maximum downward velocity and acceleration of the presser member occurs when the eccentric has rotated through 90° and the presser member is decelerated during the next 90° of rotation. Since the die is not struck until the presser is almost at the bottom of its downward stroke, i. e., at about 120° of rotation, it will be readily seen that the machine does not strike the die at the most desirable moment, namely, when the presser is traveling at its greatest speed. Consequently all power used to build the speed of the presser member up beyond the speed at which it is moving when it strikes the die is wasted.

Accordingly, the invention provides a clicking machine having a cutting block, a vertically reciprocable supporting post, a presser member

loosely pivoted for swinging movement about the post, and means for reciprocating said post so constructed and arranged that the major part of the downward portion of the reciprocatory movement is continuously accelerated.

By continuing to accelerate the presser member beyond the first half of its downward stroke, it is made certain that the presser member will strike the die at a moment when it is either accelerating or is traveling at its maximum velocity rather than when it is decelerating. The necessity of building up excess speed to insure sufficient speed at the moment the die is struck is thus entirely eliminated.

Another obstacle to the satisfactory operation of machines of this sort lies in the fact that the operator, in order to increase his speed of production, will frequently actuate the starting mechanism before the horizontal movement of the beam has stopped. The consequent combination of horizontal and downward movement results in the delivery of a diagonal blow rather than a straight one. In extreme cases, the presser member may strike only a part of the die. The disadvantages of this are obvious. The cut is apt to be rough, and generally of poor quality, the die may be moved sideways slightly, or one side of the die may be embedded in the cutting block. In addition, if a double edge die is being used, a diagonal blow tends to turn the upper edge of the die against which the presser member strikes, and thus dulls the die.

Accordingly, another feature of the invention comprises braking means carried by the post and operable by the continuous acceleration of the downward movement of the presser member, said braking means acting to prevent further horizontal movement of the presser member once the latter has begun its downward movement.

By providing such braking mechanism, all horizontal movement of the presser member is stopped once the machine has begun its cycle of operation and the possibility of diagonal blows is eliminated. Furthermore since the continuous acceleration of the presser member causes the braking means to function, the action of the latter is positive and does not depend on the operator for its effective use.

The invention will be further described with reference to the accompanying drawings, in which

Fig. 1 is a side elevation of a clicking machine, a portion being broken away to show the cam drive;

Fig. 2 is a front elevation of the machine, por-

tions being broken away to show the cam drive and the means for adjusting the cutting block;

Fig. 3 is a plan view of the machine; and

Fig. 4 is a chart of the driving cam.

- 5 As shown in Figs. 1 and 2, the machine comprises a frame 10 the forward portion of which supports a cutting block 12, on which the sheet material L to be operated upon is held. The cutting block 12 may be raised or lowered to suit 10 the height of the die 14 and the thickness of the work by means of a hand wheel 15 connected by a pair of worms (not shown) and worm wheels 16 to jack screws 18 on which the cutting block is supported. The mechanism disclosed for adjusting 15 the height of the cutting block is essentially similar to that disclosed in Letters Patent of the United States No. 2,021,138, issued November 19, 1935, on the application of Milton H. Ballard and Donald G. McLean.
- 20 Positioned over the cutting block is a presser member or beam 20 mounted on a pin 22 in one end of a post 24. The post is arranged for vertical reciprocating movement and is held in position against horizontal movement by a rear guide surface 26, side guide surfaces 28 and a front guide plate 30 affixed to the frame 10 by bolts 32. The lower end of the post is hollow and forms a yoke 34, which serves as a support for an axle 36 carrying an upper cam roll 38 and an axle 40 carrying a lower cam roll 42. A cam 44, with which cam rolls 38 and 42 are engaged, is mounted on a drive shaft 46. Loosely mounted upon the outer end of the shaft 46 is a fly wheel 48 adapted to be continuously driven by a belt or 25 by an electric motor, not shown, and arranged to be operatively connected, upon actuation of a starting handle 49, by means of a clutch 50, of the type disclosed in the above-mentioned Patent No. 2,021,138.
- 40 The presser member or beam 20 extending over the cutting block 12 has a pressing surface substantially smaller than the surface of the cutting block 12 and is mounted for horizontal swinging movement about pin 22 so that it can be positioned over a die placed on any part of the cutting block 12. The presser member 20 extends rearward from the pin 22 for a short distance only, and is so constructed that its center of mass is located well forward of the pin.
- 50 The pin 22, which serves as a mounting for the presser beam, is threaded into a boss 52 on the post 24, and holds the presser member in place on the post by means of a head 54 and a flange 56, the latter being fitted into a cup shaped spherical bearing surface 58 in the presser member. As shown in an exaggerated state in Figs. 1 and 2 for purposes of illustration, the presser member fits loosely on the pin, so that it can tilt or rock rearwardly about horizontal axes to a slight extent. In order to insure freedom of rotation of the presser member about the pin, roller bearings 60 are provided near the top of the pin, and at the bottom is located a ball thrust bearing 62 against which a boss 64 on the presser 55 member rests.

On the rearmost portion of the post is positioned an arcuate braking surface or track 72 which is concentric with the pin 22. Directly above the track on the under surface of the rear of the presser member is a slight projection 74, arranged so as to be over a portion of the braking track 72 at all times, regardless of the position of the presser member 20. When the presser beam 20 is at rest in its normal or upmost position, there is a small clearance of a few thou-

sands of an inch between the projection 74 and braking surface 72.

As has already been stated, cam 44 is mounted on drive shaft 46 which is carried on bearings 76 in the rear wall 18 of the frame 10 and in a supporting member 80 integral with the wall. The cam 44 is mounted on the drive shaft 46 in such position that the portion of its periphery nearest to the axis of rotation, i. e., that part in the vicinity of 0° in Fig. 4 is at the bottom when the machine is at rest. During the initial portion of its rotation, the cam imparts no movement through post 24 to presser member 20. At the point indicated by 35°, however, there is begun a rapidly accelerated downward movement which reaches its peak velocity at approximately 110°. The downward movement is continued at this velocity during the next 30°, during which time the presser member strikes the die. Deceleration occurs between 130° and 140° at which time presser member 20 has been carried to its lowest position. From 140° to 215°, there is a dwell during which no movement is imparted to the presser member, and at 215° the presser member 20 begins its return to normal position, which return is complete at 320°. The remainder of the revolution of the cam 44 is a dwell.

It will be noted that there is a dwell in the cam 44 for a considerable distance either side of its normal position of rest at 0°. In practice it sometimes happens that the clutch will permit the cam to overrun somewhat, or will stop it before it reaches its normal position of rest. The dwell at this point thus insures that the presser member will stop in its upmost position, without beginning a second downward movement which might endanger the hands of an operator.

In operation, sheet material L is placed on the cutting block 12 and a die 14 set on it in the desired position, the presser member or beam 20 being swung to one side at this time. The operator then grasps handle 49 or any other convenient portion of the presser member or beam and swings the latter into position directly over die 14. The operator then depresses handle 49 which is connected to a lever 82 having a forked end 84 making engagement with a link 86. The link 86 is pivoted at 88 on the frame and has a rearwardly extending portion 90 which is connected to the clutch 50 by a link 92, the handle 49 being held in normal position by a spring 94. As cam 44 begins to rotate, it draws post 24 downwardly, tightening the fit between the flange 56 and bearing surface 58. Since the machine is operated at a speed such that the downward acceleration of the post 24 and the presser member 20 is greater than the gravitational acceleration, the inertia of the presser member comes into play, offering considerable resistance to the downward pull of the post.

As has been pointed out, the presser member is supported on the pin 22 well rearward of the center of mass of the presser member, so that, in accordance with well-known physical principles, when the beam is pulled down at its point of support adjacent to its rearward end at a rate faster than the rate of gravitational fall, it tends to rock rearwardly. In other words the downward pull of the post operates to overcome the inertia of the rearward portion of the presser member before the forward portion is affected. Since the loose fit of the pin 22 permits slight movements about horizontal axes the presser member rocks rearwardly to a predetermined extent to bring its braking surface 74 into engagement with the

braking surface 12 on the post. The frictional engagement thus created between the braking surfaces prevents further horizontal movement of the presser member so that the latter must, of necessity, deliver a perpendicular blow to the die. Furthermore, since the presser member strikes the die when the cam 44 has rotated through approximately 120°, the blow will be delivered when the presser member 20 is moving at its maximum velocity as is shown by Fig. 4.

It will thus readily be seen that the invention provides a simple, sure means of avoiding glancing or diagonal blows on the die and the disadvantages attendant thereupon. Furthermore the efficiency of the machine will be at a maximum since the presser member strikes the die when traveling at its peak velocity instead of at a time when the presser member is decelerating as is the case in the type of machine now in general use.

Having thus described my invention, what I claim as new and desire to secure by Letters Patent of the United States is:

1. In a clicking machine, a vertically reciprocable post, a presser member pivoted on said post by means permitting slight tilting about horizontal axes, means for reciprocating said post, and a braking surface carried by the post and constructed and arranged to engage with a corresponding surface on the bottom of the presser member as the presser member begins its downward movement.

2. In a clicking machine, a swinging presser beam, means for imparting a continuously accelerated downward movement to said presser beam, and a brake constructed and arranged to check swinging movement of said beam and actuated by said continuously accelerated downward movement of said presser member.

3. In a clicking machine, a presser beam, a cam constructed and arranged to impart to said presser beam a continuously accelerated downward movement, and means actuated by said continuous downward acceleration for preventing horizontal movement of said presser member after it has begun its downward movement.

4. In a clicking machine, a vertically reciprocable post, a presser member mounted to rotate on and to reciprocate with said post and to rock slightly about axes substantially horizontal, cam rollers connected to said post, a cam constructed and arranged to impart to said cam rollers a cycle of motion comprising a dwell and a continuously accelerated downward movement, and a braking surface constructed and arranged to engage the bottom of said presser member when the inertia of said presser member causes it to rock horizontally as said presser member begins its downward movement.

5. In a clicking machine, a vertically reciprocable post, a presser member mounted for horizontal swinging movement on said post by means permitting slight tilting of said presser member about horizontal axes and having its center of mass spaced from said post, cam rollers connected to said post, a drive cam constructed and arranged to impart a continuously accelerated downward movement to said rollers, and an arcuate braking surface carried by said post and constructed and arranged to engage a similar surface on the bottom of said presser member on the side of said post opposite from the center of mass of said presser member when the inertia of said presser member causes it to tilt slightly as it begins its downward movement.

6. In a clicking machine, a vertically reciproc-

cating post, a presser member pivotally mounted for swinging movement on said post by means permitting slight tilting about horizontal axes, and an arcuate braking track carried by said post constructed and arranged to engage with the bottom of said presser member and having its center of curvature at said post.

7. In a clicking machine, a vertically reciprocating post, a presser member mounted for horizontal swinging movement on said post by means permitting slight tilting of said presser member about horizontal axes, and an arcuate braking surface carried by said post and spaced apart from a similar surface on said presser member a slight distance such that when inertia causes said presser member to tilt as it begins its downward movement the two surfaces will engage with each other.

8. In a clicking machine, a vertically reciprocating post, a cutting block, a presser member mounted for horizontal swinging movement on said post by means permitting slight tilting of said presser member about horizontal axes and having its center of mass located above said cutting block, and an arcuate braking surface carried by said post and spaced apart from a similar surface on the bottom of said presser member a slight distance such that when inertia causes said presser member to tilt as it begins its downward movement, the two surfaces will engage with each other.

9. In a clicking machine, a work support, a presser member mounted for movement from a position away from said work support to a position where it effects an operation upon a work piece on the work support, and means for imparting to said presser member a downward movement which is continuously accelerated from the beginning of the movement to the operation on said work piece, and which maintains its maximum velocity for a substantial part of its operation on said work piece.

10. In a clicking machine, a vertically reciprocable post, a presser member loosely mounted for swinging movement on said post, a curved bearing surface carried by said post, a complementary recess in said presser member such that said presser member may tilt slightly about horizontal axes, and means for imparting to said presser member a continuously accelerated downward movement.

11. In a clicking machine, a work support, a vertically reciprocable post, a presser member resting on the upper end surface of said post, a pin loosely securing said presser member for swinging movement on said post, a head on said pin having a spherical bearing surface, a complementary recess in said presser member such that said presser member may tilt slightly about horizontal axes, and means for imparting to said presser member a downward movement which is continuously accelerated up to the moment of impact with a work piece on said support.

12. In a clicking machine, a vertically reciprocable post, a presser member pivotally mounted on said post, a curved bearing surface carried by said post, a complementary recess in said presser member such that said presser member may tilt slightly about horizontal axes, said presser member having its center of mass spaced apart from said post, and means for imparting a continuously accelerated downward movement to said presser member such that the inertia of said presser member will cause the latter to tilt as it begins said downward movement.

13. In a clicking machine, a vertically reciprocating post, a cutting block, a presser member pivoted on said post for horizontal movement, a spherical bearing surface carried by said post, and a complementary recess in said presser member such that said presser member may tilt to a predetermined extent about horizontal axes, said presser member having its center of mass positioned above said block at a point such that the 10 inertia of said presser member will cause the latter to tilt on a horizontal axis as it begins its downward movement.
14. In a press of the character described for cutting blanks from thin sheet material comprising a work table and a presser member adapted to strike a blow on a cutting die positioned over work on said table, and means for accelerating the presser member during its downward movement, said work table being positioned 15 relative to the vertical movement of the presser member so that the presser member will momentarily engage the die to strike a sharp blow

thereon at a time when the presser member has attained its maximum velocity and is almost at the end of its downward stroke.

15. In a press of the character described for cutting blanks from thin sheet material comprising a work table and a presser member adapted to strike a blow on a cutting die positioned over work on said table, cam rollers connected to said presser member, and a cam in engagement with the rollers for driving the 10 presser member, the portion of said cam in engagement with said rollers during downward movement of the presser member having its radius increased sufficiently to accelerate and maintain the presser member at a maximum 15 velocity throughout an angular displacement of the cam greater than 90° so that the presser member will engage the die at a time when the presser member has attained said maximum velocity.

20

MIETH MAESER.
